[57] CLAIM

[**] Term: **14 Years**

The ornamental design for a top portion of yellow jacket control trap, as shown and described.

[21] Appl. No.: **34,227**

DESCRIPTION

[22] Filed: **Jan. 30, 1995**

FIG. 1 is a front and sides elevational view of a top portion of yellow jacket control trap, showing my new design, with the opposing rear and sides being a mirror image thereof; FIG. 2 is a top plan view thereof; FIG. 3 is a bottom plan view thereof; and, FIG. 4 is a perspective view thereof.
